EDWARD C. JONES, OF HOQUIAM, WASHINGTON

SPACEBAND RAIL FOR TYPESETTING MACHINES

Application filed November 4, 1930. Serial No. 493,358.

This invention relates to spaceband rails for typesetting machines.

In typesetting machines of the kind to which my invention relates, namely, the so-called linotype machines, a spaceband rail is employed which in the standard machines in common use has a rounded upper edge and is of approximately 115 thousandths of an inch in thickness between its upper and lower edges and varies in height from 728 thousandths of an inch to approximately 918 thousandths of an inch. The spacebands which are used on this machine, and which slide on the said spaceband rail for transfer from the first elevator to the spaceband box, have slotted or forked lower ends to straddle the rail, and the slots of such forked ends of the spacebands vary usually in width from an original width of 128 thousandths of an inch up to a width of 130 thousandths of an inch or greater according to the age of the spaceband and degree of wear thereof. This original excess in width of the spaceband slot over that of the rail is provided in order that the spaceband may have a certain degree of lateral pivotal motion on the rail for flexibility of travel. The width of the spaceband slot relative to that of the rail, however, is such in conjunction with the reduced width of the rounded upper edge of the rail that the spaceband is permitted to twist or tilt laterally on the rail to a degree, increased by wear, that a binding of the spacebands on the rail frequently takes place. When this "spaceband trouble", as it is known, occurs, there is a stoppage of feed of the spacebands which must be manually corrected from time to time by the operator, resulting in loss of time and liability of irregularities in the action of the machine, and bending or breakage of spacebands is also liable to happen with choking of the feed from dropping of broken parts of spacebands onto the first elevator in the transfer of the line of matrices from the first elevator to the second elevator. The use of side springs for the purpose of preventing spaceband trouble of the character described has been resorted to, but these add to the complexity of the machine.

Another difficulty encountered in the travel

of the spacebands is the tendency of the spacebands to swing too high as they leave the rail and enter the spacebox whereby they are liable to jam or be bent or broken.

One object of my invention is to provide a spaceband rail which allows ample freedom of motion of the spacebands, while preventing lateral tilting motion of the spacebands to such a degree as to cause them to bind, and without the necessity of using a side spring such as is sometimes employed for the purpose.

Another object of the invention is to provide a spaceband rail which reduces wear and tear on the spacebands and prevents breakage thereof and the deleterious consequences resulting therefrom.

Still another object of the invention is to provide a spaceband rail which will fit the usual grooved rail supporting block and which eliminates or reduces spaceband troubles to such an extent as to increase the setting capacity of the machine ten per cent or more per working day.

Still another object of the invention is to provide means for limiting the upswing movement in the passage of the spacebands from the rail to the space box, thereby preventing the stated difficulties encountered at this point in their course of travel.

The invention consists of the features of construction, combination and arrangement of parts, hereinafter fully described and claimed, reference being had to the accompanying drawing, in which:

Fig. 1 is a vertical transverse section through the rail supporting block and spaceband box and showing my improved rail therein and a spaceband engaging the same.

Fig. 2 is a cross-section through the rail and forked lower end of a spaceband engaging the same on an enlarged scale.

Fig. 3 is a top plan view of my improved rail and a horizontal transverse section through the forked lower end of a spaceband engaging the same, showing the relative width of the slot in the spaceband and that of the portion of the rail which it engages.

Fig. 4 is a side view of my improved rail. Fig. 5 is a view similar to Fig. 2 of an ordi-

nary construction of rail and a spaceband engaging the same.

Fig. 6 is a plan view of the rail shown in Fig. 5 and a horizontal section through the spaceband thereon, showing in dotted lines the lateral tilting and binding of the spaceband which my invention is designed to avoid.

Referring now more particularly to the drawing, 1 designates the intermediate channel or guideway of a linotype machine, 2 the space rail supporting bar at the base of the channel, 3 a space rail constructed in accordance with my invention, and 4 a spaceband having a lower bifurcated end to straddle and slide upon the upper portion of the rail, the slot 5 in the bifurcated end of the spaceband being of a depth substantially equal to that of the upper half of the rail. The bar 2, as shown, is slotted or grooved at 6 to receive the lower edge of the rail, which is thereby fitted in position. The lower half of the rail may be provided as usual with openings 7 for passage of fastening devices to hold it from upward and endwise displacement.

In order that a better understanding of the invention may be obtained, reference is made to Figs. 5 and 6 of the drawing showing a space rail 3^a and spaceband 4^a of standard type. This standard rail is of a width of 0.115 of an inch to fit the correspondingly sized groove or slot 6 in the bar 2, and is provided with a transversely curved or rounded upper edge, while the width of the slot 5^a in the spaceband 4^a is initially 0.118 of an inch. Due to this rounded form of the upper edge of the rail and relative widths of the upper half of the rail and slot in the spaceband, the spaceband is permitted to tilt laterally from a normal position at right angles to the rail, as shown in full lines in Fig. 6, to a position at an angle to the rail, as shown in dotted lines in Fig. 6, which tendency of the spaceband to tilt is increased with increase of looseness due to wear on the rail and walls of the slotted end of the spaceband, whereby the width of the former is increased and that of the latter decreased. As a result of this tilting motion of assembled spacebands the spacebands bind or "ball up" and cause stoppage of the travel of the spaceband and matrices. This occurs quite frequently in some machines and requires the attention of the operator who must periodically release the "balled" parts, causing much trouble and loss of time in the setting action. Another objection is that in a transfer action of the spaceband as it leaves the space rail and enters the spaceband box, the spaceband is liable to swing too high and cause stoppage at this point. Besides, these improper motions of the spacebands often cause twisting and breaking of the spacebands, and, in case of breakage of spacebands, parts thereof fall onto the first elevator and cause choking of

the feed between the first and second elevators.

My invention is designed to overcome these objections and the spaceband rail 3 is made of novel construction for the purpose.

The rail 3 may be of standard length (9 $\frac{3}{16}$ inches) and height (from 728 to about 918 thousandths of an inch) and provided with the usual beveled ends 8 to facilitate the sliding of the spacebands on and off the same, and the lower half 9 of the rail is made of standard width (115 thousandths of an inch) to fit the groove or slot 6 in the standard rail supporting bar 2. The upper half 10 of the rail, however, is of greater width or thickness than its lower half, or from 118 to 128 thousandths of an inch and is provided with a square, i. e., straight transverse upper edge 11 arranged at right angles to its sides. A rail with an upper half of 0.118 of an inch thickness will fit the slot 5 of the spaceband sufficiently snug in view of the square form of the edge 11 to prevent a new or unworn spaceband from turning or twisting to an undue extent and the square edge will prevent it from laterally tilting on the rail, so that even when the spaceband and/or rail are worn to certain degrees the spaceband may turn only to an extent to ensure ease of motion and not to a sufficient extent to cause it to bind on the rail. Balling up of the spaceband and breakage of the bands from twisting will accordingly be prevented, as well as time losses and labor spent in releasing balled spacebands and removing broken parts. Rails with upper portions of varying thicknesses above 0.118 to 0.128 are employed to enable the improved results to be obtained on machines employing old and worn bands. To prevent the spacebands from swinging too high as they leave the spaceband rail and enter the spaceband box, I provide the spaceband and rail with a stop or retarding pin 12 which touches the lower end of each spaceband as it leaves the rail and holds the lower end of the spaceband back until the upper end thereof is pulled into the spaceband box far enough to permit the band to slide freely over said pin.

A spaceband rail embodying my improved construction ensures proper transfer of the spacebands from the first elevator to the spaceband box and thus does away with balling and other spaceband troubles without the use of a side spring as used on all typesetting machines employing such spacebands. Such rails have been in daily use for many months on the typesetting machines of a newspaper plant with an entire elimination of spaceband jamming, breakages and other troubles and with the result of obviating stoppages and enabling an operator to set ten percent more type than was possible with the same machines before the rails were installed.

Having thus fully described my invention,
I claim:—

In a typesetting machine, a spaceband guide including a grooved bar, a rail having a lower portion fitted in the groove of the bar and an upper portion of a width greater than said lower portion, and a spaceband having a lower slotted end to slide on the upper edge of the bar, said upper portion of the bar of greater width having a straight transverse edge and of such width with respect to the slot of the spaceband as to prevent the spaceband from tilting laterally and binding on the rail, and a retarding pin on the rail to engage the lower end of each spaceband as it leaves the rail and limit the upward movement of the spaceband and hold said end of the spaceband back until the upper end thereof is pulled far enough into the spaceband box of the machine to permit the band to slide freely over said pin.

In testimony whereof I affix my signature.
EDWARD C. JONES.
